ABSTRACT OF THE DISCLOSURE

A process for the manufacture of phenylhydrazine by cathodic reduction with separation of cathode and anode spaces by a diaphragm wherein diazoaminobenzene dissolved in an electrolyte is reduced on solid electrodes.

The present invention relates to a process for the manufacture of phenylhydrazine.

The electrolytic reduction of hydrochloric acid solutions of benzene diazonium chloride to yield phenylhydrazine is known. (P. Rietschi, G. Trümpler in *Helvetica 36* (1953) pages 1649–1658). To avoid secondary reactions of the phenylhydrazine formed, the solution must be pressed from below through the mercury cathode at 0–5° C., a process which is not overly attractive from a technical point of view because of the low space-time yields.

It is also known that the reduction of benzene normal diazotate in alkaline solution at 0–5° C. takes place with low yields of phenylhydrazine (F. Fichter, E. Willi in *Helvetica 17* (1934) page 1418). Good yields can be obtained after rearrangement into the anti-derivative but only at a temperature below +5° C., which involves cooling problems.

The technical accomplishment of the diazotate reduction is additionally impeded by the fact that it is an indirect electro-chemical reduction (F. Fichter, *Organische Elektrochemie* 1942, page 223). The diazotate is not reduced directly by the absorption of electrons from the cathode but by the cathodically produced sodium amalgam. It is therefore not surprising that poor yields are obtained when other cathode materials that are better suited for a technical performance are used in the reduction of aromatic diazotates (F. Fichter, E. Willi in *Helvetica 17* (1934) page 1418).

It is likewise known that in the polarographic reduction on the dropping mercury electrode diazoaminobenzene accepts 4 electrons and 4 protons. It is said that in this reaction phenylhydrazine and aniline are formed (as to the protonation problems in electrode processes confer "Investigations With Diazoaminobenzenes and Unsaturated Ketones"—L. Holleck; *Elektrochemisches Symposium der GDCh* of Oct. 13–15, 1971 in the Nuclear Research Plant Jülich).

Still further it is known that phenylhydrazine undergoes relatively easy reductive scission. With hydrogen on nickel, aniline and ammonia are obtained in a quantitative yield at atmospheric pressure and normal temperature. (H. Rupe, E. Hodel in *Helvetica 6* (1923) page 873). With zinc and hydrochloric acid the quantitative scission of phenylhydrazine can also be obtained (E. Fischer, *Liebigs Annalen 239* (1887) page 248).

In the electrochemical reduction of aromatic diazotates on lead or cadmium the escape of ammonia indi-

cates the cathodical scission of the hydrazine grouping; therefore, the yields of arylhydrazine are only in the range of from 20–27%, whereas under identical conditions on mercury a yield of over 90% of phenylhydrazine can be reached. (F. Fichter, E. Willi in *Helvetica 17* (1934) page 1418).

It has now surprisingly been found that phenylhydrazine can be obtained by cathodic reduction in a good yield by reducing diazoaminobenzene, dissolved in an electrolyte on solid electrode materials such as lead, zinc, zinc-titanium alloy, cadmium, tin and surprisingly also copper and graphite. It is known that copper and graphite have a distinctly lower hydrogen over-voltage than, for example, lead or mercury and, therefore, they ought to be less suitable for the reduction of diazoaminobenzene. Nevertheless, the use of copper or graphite as electrode material gives very high yields of phenylhydrazine even in galvanostatic electrolysis, i.e. under technically interesting conditions.

In contradistinction to the cathodic reduction of diazonium salts and diazotates, the electrolysis temperature can be varied in a wide range and its upper limit is only given by the thermal decomposition of the diazoaminobenzene. A temperature in the range of from –20° to +100° C., especially +15° to +60° C. is preferred. The electrolysis is preferably carried out with aqueous electrolytes. To improve the solubility of the diazoaminobenzene in the catholyte the common solvents such as alcohols, ethers, carboxylic acid amides and/or nitriles or mixtures thereof are suitably added as organic solvents.

The diazoaminobenzene can be prepared either before-hand according to known processes in a separate reaction or directly in the catholyte from aniline. Besides the high yield and the largely variable electrolysis temperature, the process of the invention therefore has the further advantage that the aniline obtained in the cathodic dissociation of diazoaminobenzene can be used again for preparing fresh diazoaminobenzene.

A sufficient conductivity of the catholyte is preferably obtained in known manner by adding suitable conducting salts. The pH-value of the catholyte has to be chosen in such a manner that the diazoaminobenzene cannot be split to give benzenediazonium salt and aniline, a pH-value above 5, especially about 6 to 14 being preferred. Higher pH-values are also possible but they do not offer any advantage. Suitable conducting salts are preferably alkali metal and ammonium hydroxides as well as organic bases, for example the various tetraalkyl ammonium hydroxides.

As electrolysis cells there can be used all common cells with separation of cathode and anode space by diaphragms. As diaphragms there can be used all common materials provided that they are stable to alkali and/or acids as well as the used organic solvents. Especially suitable are ion exchange diaphragms, more particularly anion exchange diaphragms.

In the following examples the yields of phenylhydrazine were obtained without choosing the optimum conditions. It is obvious that by variation of the electrolysis conditions better yields can be obtained. The phenylhydrazine can be obtained not only in the form of the hydrochloride as described in the following examples but also by separation from the aniline without acidifying the catholyte, for example by distilling off the solvent from the catholyte directly and working up by distillation the mixture of phenylhydrazine and aniline then separating.

The material yields are calculated on the amount of diazoaminobenzene used as in the chosen acid working-up of the catholyte, this is resplit into benzenediazonium salt and aniline so that the unreacted portion of the starting substance is not determined directly.

EXAMPLE 1

The electrolysis was carried out in the presence of an inert gas in a round glass cell having a capacity of about 350 ml. and provided with cooling jacket on a lead disc of about 45 cm.². Stirring was performed with a magnetic stirrer, the rotating core of which rested on the disc. The cell was provided with a lateral neck for inserting a Luggin-capillary for the reference electrode (silver/silver chloride). The anode space consisted of a polyethylene tube having a lower diameter of about 5 cm., which tube was closed at the lower end by an anion exchange diaphragm (Nepton A111 BZL 183) by means of a screw collar ring. The opposite end of the tube was screwed into a polyethylene stopper provided with standard ground joint so that the cell was tightly closed. The stopper had the necessary standard ground borings for thermometer, bubble counter and inert gas inlet. As anode a stainless steel (V4A) spiral was used. The anolyte was 3 N KOH.

The catholyte contained 0.1 mol (19.7 g.) diazoaminobenzene dissolved in 200 ml. of a mixture of methanol/3 N KOH in a ratio of 20:1. The electrolysis temperature was in the range of from 28°–33° C. 10.7 a./hr. of current were passed potentiostatically at –1800 mv. (against Ag/AgCl) through the cell, whereupon the initially deep blackish red nontransparent solution had turned pink.

The solution was acidified with HCl, methanol was distilled off, the residue was taken up in concentrated hydrochloric acid and the phenylhydrazine hydrochloride remaining as a precipitate was filtered off with suction. The salt was suspended in water, the suspension was rendered alkaline with NaOH whereby the free phenylhydrazine separated. It was repeatedly extracted with ether, the combined ether phases were dried and the ether was distilled off. 10.2 g. of phenylhydrazine were obtained.

The filtrate remaining behind after the separation of the phenylhydrazine hydrochloride was rendered alkaline with NaOH and the separated aniline was extracted with ether. After drying and distilling off of the ether 8.85 g. aniline were obtained. The yield of 10.2 g. of phenylhydrazine corresponds to a material yield of 94% or a current efficiency of 94%.

EXAMPLE 2

Electrolysis was performed in the cell described in Example 1 with the exception that a copper disc having a surface of 45 cm.² was used. 12 a./hr. were passed galvanostatically at 2 ampere through the mixture consisting of 200 ml. methanol/3 N KOH (20:1) and 19.7 g. (0.1 mol) diazoaminobenzene. The material yield of phenylhydrazine was 83%, the current efficiency 73%.

EXAMPLE 3

Electrolysis was carried out in the cell described in Example 1, with the exception that an electrographite disc having a surface of 40 cm.² was used. 11.5 a./hr. were passed galvanostatically at 2 ampere through the mixture consisting of 200 ml. methanol/3 N KOH (20:1) and

19.7 g. (0.1 mol) diazoaminobenzene. The material yield of phenylhydrazine was 89%, the current efficiency 83%.

EXAMPLE 4

5 Electrolysis was carried out as described in Example 2 but using a zinc disc having a surface of 45 cm.²; phenylhydrazine was obtained in an 78% current efficiency.

EXAMPLE 5

10 Electrolysis was carried out in a flow cell consisting of 2 equally large square polyethylene halves between which the anion exchange diaphragm (commercial name Nepton A 111 BZL 183) was clamped. The effective cathode surface was 115 cm.². To obtain a uniform substance transport the electrode spaces were divided in four trajectories by conducting strips resting on the electrodes and the diaphragm. The distance cathode to diaphragm was 6 mm. Lead was used as cathode material, platinum as anode material.

20 The electrolytes (anolyte: 700 ml. 3 N KOH; catholyte: 1000 ml. 0.5 molar diazoaminobenzene in methanol/3 N KOH (20:1)) were circulated by a pump with a flow speed of about 15 cm. per second. 6.7 a./hr. current were passed galvanostatically at 18 amperes. The reaction mixture was worked-up as in Example 1 whereby phenylhydrazine was obtained in a material yield of 91.5% or a current efficiency of 73%.

Phenylhydrazine is a valuable intermediate product and starting product for pharmaceutical and dyestuffs.

30 What is claimed is:

1. Process for the manufacture of phenylhydrazine by cathodic reduction with separation of cathode and anode spaces by diaphragm which comprises reducing at a cathode selected from the group consisting of cadmium, copper, graphite, lead, tin, zinc and an alloy of zinc and

35 titanium material diazoaminobenzene dissolved in an electrolyte comprising water, an organic cosolvent, and a conductive compound selected from the group consisting of alkali metal hydroxide, ammonium hydroxide, an organic base and mixtures thereof at a pH above 5 and a temperature between –20 to +100° C.

2. The process of claim 1, wherein graphite is used as cathode material.

3. The process of claim 1 wherein the pH of the electrolyte is above 6.

4. The process of claim 1, wherein the conducting compound is an alkali metal hydroxide.

5. The process of claim 1, wherein an ion exchange material is used as diaphragm.
